SURGICAL BUST PAD

Helen G. Creamer, Pasadena, Calif.

Application April 4, 1955, Serial No. 499,141

16 Claims. (Cl. 3—36)

This invention relates to a surgical bust pad and more particularly to a surgical bust pad which is to be worn after removal of the normal breast by surgery and which has the appearance, texture and weight of a normal human breast.

Present types of artificial busts utilize a bust pad filled with a packing such as felt or a liquid, to provide weight and give resiliency to the pad. However, such artificial busts have the disadvantage that the back surface of the bust pad contacts the tender skin remaining after removal of the human breast and causes irritation of this skin. Also, the type of packing used in prior devices results in expensive and complex construction of the bust pad and the packing has a tendency to become contaminated after being worn.

By the present invention, a bust pad is provided in which the structural components of the pad are positioned away from the area of surgical operation to prevent irritation of the tender skin. The bust pad also incorporates novel packing to give the needed weight and resiliency to the pad. More particularly the bust pad consists of a single continuous layer in the shape of a human breast, which layer is fabricated from foam latex, synthetic foamed plastic material or the like and is weighted with shot, heavy sand or other finely divided substances attached to said layer. In the preferred form of the invention, the pad is weighted by shot which is carried within the interior of the wall of the pad at a position such that the center of gravity of the pad will fall at the portion of the pad lying below the nipple. The pad is covered with a suitable covering material, such as silk or rayon cloth, and is inserted into the cup of a brassiere. Because of the location of the weight within the pad, the behavior of the pad in the brassiere cup will be essentially that of a normal breast and the pad can be worn after a mastectomy to give a lifelike appearance. In addition, the edges of the bust pad are shaped to conform to the contour of the chest portions surrounding the area of surgery so that the pad will fit closely to the body of the wearer and will give the appearance of a normal breast.

It is therefore an object of the present invention to provide a surgical bust pad which is weighted with heavy solid particles secured to the pad.

Another object of the invention is the provision of a bust pad which is constructed of a single continuous surface in the shape of the human breast and which is weighted by heavy solid particles integral with the bust pad.

A further object of the invention is to provide a surgical bust pad formed of a single continuous layer which is concave so that the pad does not bear against and irritate the area of surgery.

A still further object of the invention is to provide a bust pad in the shape of a human breast and comprised of a single layer which is weighted by heavy particles integral with the layer and located within the layer at a

2

position corresponding to the center of gravity of a normal breast.

Another object of the invention is the provision of a surgical bust pad comprised of a single continuous layer of material in the shape of a human breast and having the edges of the layer skinned and shaped to conform to the contour of the chest portion surrounding the area of surgery in the same manner as would the normal human breast so that the pad appears as a continuation of the remaining chest surface.

These and other objects of the invention not specifically set forth above will become readily apparent from the accompanying description and drawings in which:

Figure 1 is a projected elevational view showing the back surface of the three sections which are secured together to form the surgical bust pad.

Figure 2 is a horizontal section along line 2—2 of Figure 1 showing the manner in which the weight particles are made integral with each of the lower sections of the pad.

Figure 3 is a rear elevational view of the bust pad with the three sections secured together to form a single, continuous layer in the shape of a human breast.

Figure 4 is a front elevational view of the bust pad illustrated in Figure 3 and showing the position of the weight particles directly below the nipple.

Figure 5 is a vertical section along line 5—5 of Figure 4 illustrating the flexible protective covering placed completely around the pad.

Figure 6 is a horizontal section along line 6—6 of Figure 4 illustrating the contour of the edges of the bust pad.

Referring to Figure 1, a surgical bust pad 7 is formed from an upper section 8 and two lower sections 9 and 10. Each of the sections is constructed of foam rubber, but other suitable materials such as foam plastics and synthetic foam can be utilized for this purpose. Before the sections are assembled, sections 9 and 10 are split longitudinally over the areas 11 and 12, respectively. Each of the longitudinally split areas has surfaces 13 and 14 which are first coated with a rubber or other suitable flexible cement and a layer of weight particles 15 is placed on the coated surface 14. The surfaces are then pressed together to close the split area and the weight particles become an integral part of the wall of the section. In Figure 2, the weight particles are shown as heavy shot but sand or other heavy, finely divided material can also be used as a second layer 15' of particles can be applied to the other surface 13 before the surfaces 13 and 14 are sealed together in the event that additional weight is required. Of course, a single layer of larger shot could also be used to increase the weight. The rubber cement serves to grip the weight particles so that they can be applied in an even layer and also serves to seal the surfaces 13 and 14 around the weighted particles. Because of the manner in which the particles are incorporated, they do not distort the contour or interfere with the texture of the pad sections 9 and 10.

After the weight particles are incorporated, the edges 16 and 17 of sections 9 and 10, respectively, are secured together by rubber cement to form a seam 18 and because these edges curve away from each other the sections 9 and 10, when secured together, assume a shape similar to the lower portion of a normal breast. The lower edge 19 of section 8 is then secured to the upper edges 20 and 21 of section 9 and 10 respectively, by rubber cement to form a seam 22. After being thus secured, the upper section assumes a shape similar to the upper portion of a normal breast.

In order that the bust pad will fit closely to the body

surface of the wearer, the edge 23 of section 8 and the edge 24 of section 9 are tapered so that these edges will be parallel to and abut the chest of the wearer when the sections are shaped to form the bust pad. Also, the edge 25 of section 10 has a portion 25' which is similarly tapered to abut the chest of the wearer. Another portion 25" of edge 25 and edge 26 of section 8 are tapered to a feather edge 27, at the lateral side so that these edges rest flat against the rib cage. Thus, the bust pad is shaped to fit against the surface contours of the body to simulate the shape of a normal breast. The complete pad is encased in a cloth cover 28 which conforms to the front surface of the pad and projects across the back of the pad. The covered bust pad can be held loosely in a brassiere cup or the cover 28 can be equipped with hooks or fasteners so that the pad can be secured to the brassiere.

When the bust pad is worn in a brassiere the weight particles 15, spread over the areas 11 and 12, have a center of gravity located below the nipple where the bust bulges naturally, so that the pad gives the appearance of a normal breast. The effect of the pad inserted in a brassiere cup is one of naturalness and tends to balance the brassiere and compensate for the weight of the remaining breast. The total weight of particles 15 added to the pad will normally increase as the size of the pad increases. It is understood that the weighted areas 11 and 12 can be varied in size and position and that the weight particles can be inserted in section 8 as well as in sections 9 and 10. For instance, each of the three sections could be split over substantially the whole area so that the weight particles would cover substantially the whole area of the bust pad. Also, while it is desirable to make the particles integral with the bust pad, the invention contemplates that the weight particles can be assembled in a separate container and attached to a position on the inner surface of the bust pad.

Since the bust pad is concave on the side next to the body, the pad has only a small area of contact against the body surface around the tender skin resulting from the surgical operation. The cover 28 is the only portion which touches this tender area and therefore this area is kept clean and cool. While a mastectomy usually leaves the chest flat or somewhat concave, the cover 28 will easily flex to the dashed line position of Figure 5 in the event that the chest emerges from surgery somewhat convex in form. While the surgical pad is primarily designed as a bust replacement, it can equally well be used to fit over a deficient breast. Because of the fact that the bust pad has an abrupt taper to edge 9 and because the edges of the bust pad do not contact the area of surgery, there is less chance of dermatitis developing.

The present invention provides a novel bust pad which behaves in much the same manner as a normal breast. The pad does not contact the tender skin resulting from surgery since the pad is constructed of a single, continuous layer which can be weighted with solid particles attached to the layer. While the pad has been described as constructed of separate sections, the complete pad can be molded with the weight particles in the desired location. Also, the invention contemplates the use of one or more large particles of solid material in place of the finely divided particles. For instance, a single solid particle in any suitable shape, such as in plate form, could be inserted into the bust pad at a position to give the desired weight effect and the particle could be shaped to the contour of the bust pad at this position if necessary. This particle could also be made flexible in order to give resiliency to the weighted area. Several such large particles could be inserted into the pad at desired locations or could be attached to the interior of the pad and both large particles and finely divided particles could be utilized in the same pad. Various other modifications are contemplated by those skilled in the art without departing

from the spirit and scope of the invention as hereinafter defined by the appended claims.

What is claimed is:

1. A bust pad comprising a continuous layer of resilient material having an external surface formed into the shape of a human breast and a plurality of rigid, inflexible particles embedded within said layer to increase the density of said layer at any desired position, at least some of said particles being individually confined by said layer and all said particles being small enough in size to permit universal flexing at said desired position solely by relative movement between the particles.
- 5 2. A bust pad as defined in claim 1 wherein said continuous layer is formed of a plurality of sections having edge connections and extending from one another to form a single layer, one or more of said sections containing said rigid particles in the interior thereof.
- 10 3. A bust pad as defined in claim 2 wherein said particles are arranged in layer form in each particle containing section with the particles randomly distributed in the layer, said particles being positioned to place the center of gravity below the nipple where the human breast naturally bulges.
- 15 4. A bust pad as defined in claim 1 wherein the edges of said layer abut the body of the wearer and said layer is contoured at the edges to appear as the normal continuation of the body surface at the edges, said layer being more concave than the breast area of the wearer so that said pad cannot contact and irritate said area.
- 20 5. A bust pad as defined in claim 4 having a soft cloth cover for said pad, said cover conforming to the outer surface of said pad and projecting away from the pad across the concave area of the back of said pad so as to lightly contact the breast area.
- 25 6. A method of weighting a bust pad constructed of a single layer of resilient material comprising splitting an area of said resilient material at the position to be weighted, placing within the split area a plurality of solid particles of greater density than said material and thereafter sealing the material together over the split area to re-unite the material over the split area.
- 30 7. A method of constructing a bust pad from a plurality of sections of resilient material comprising splitting one or more of said sections, coating the split surfaces with adhesive material, applying a plurality of solid particles of greater density than said material to said coated surfaces, sealing said coated surfaces around said particles and thereafter connecting said sections together to form said bust pad.
- 35 8. A bust pad comprising a continuous layer of resilient material having an outer surface formed into the shape of a human breast, the portion of the pad at the lateral side having a tapered interior surface forming a small angle with the outer surface of said layer so that said layer gradually increases in thickness from said lateral side to give the appearance of the slight curvature of a normal breast at the lateral side, the apex of said small angle comprising a feather edge so that no abrupt change in contour occurs between the body surface of the wearer and the pad at the lateral side.
- 40 9. A bust pad comprising a single continuous layer of resilient material having an outer surface formed into the shape of a human breast, the edge of the pad at the lateral side comprising a tapered interior surface forming a small angle with the outer surface of said layer so that said layer gradually increases in thickness from said lateral side to give the appearance of the slight curvature of a normal breast at the lateral side, the remaining edges comprising tapered edge surfaces forming angles with said outer surface larger than said small angle so that said remaining edges engage the chest surface over less area than said first mentioned edge to give the appearance of the greater curvature of a normal breast at said remaining edges, all of said edges lying against the chest surface
- 45

- 55
- 60
- 65
- 70
- 75

so that said outer surface gives the appearance of the surface of a normal breast.

10. A bust pad comprising a single continuous layer of resilient material having an exterior surface formed into the shape of a human breast, said layer having a concave interior surface positioned over the breast area of the wearer, and a plurality of rigid, inflexible particles embedded in said layer at a selected location, said particles being of greater density than said resilient material in order to increase the density of said layer at the selected location, said particles being distributed over the selected location and movable relative to one another to provide for resiliency at said location.

11. A bust pad comprising a single continuous layer of resilient material having an exterior surface formed into the shape of a human breast with nipple, and a plurality of rigid particles embedded in said layer over a selected area and at least some of the particles being individually confined by said layer, said particles being of greater density than said resilient material and being disbursed over said area for movement relative to one another to retain the flexibility of the pad in said area.

12. A bust pad as defined in claim 11 wherein said rigid particles comprise shot particles, said shot particles being arranged in layer form within said area and cemented to said resilient material.

13. A bust pad as defined in claim 11 wherein said area is entirely located at a position beneath the nipple on said pad so that the center of gravity of said pad corresponds to the location of the center of gravity of the 30 human breast.

14. A bust pad comprising a continuous layer of resilient material having an exterior surface formed into the shape of a human breast, and a plurality of rigid particles inserted into said layer over a selected area, said 5 particles being distributed in layer form over said area to increase the density thereof and to provide for flexibility of said area solely by relative movement between said particles.

15. A bust pad as defined in claim 14 wherein said 10 layer of resilient material has a concave interior surface adjacent the breast area of the wearer, said particles being distributed in layer form between said exterior and interior surfaces.

16. A bust pad as defined in claim 14 wherein said 15 selected area is defined by a slit in said layer closed around said particles.
